UNITED STATES PATENT OFFICE

151,044

DESIGN FOR A ROUTING MACHINE

William F. Huck, Forest Hills, N. Y., assignor to
R. Hoe & Co., Inc., New York, N. Y., a corpora-
tion of New York

Application July 5, 1947, Serial No. 140,107

Term of patent 14 years

(Cl. D93—2)

To all whom it may concern:

Be it known that I, William F. Huck, a citizen of the United States, residing at Forest Hills, county of Queens, and State of New York, have invented a new, original, and ornamental Design for a Routing Machine, of which the following is a specification, reference being had to the accompanying drawing, forming part thereof, in which:

Figure 1 is a front elevation of a routing machine, showing my new design;

Figure 2 is a side elevation of the routing machine of Figure 1; and

Figure 3 is a plan view thereof.

The side of the machine not shown is substantially like the side shown.

I claim:

The ornamental design for a routing machine, as shown and described.

WILLIAM F. HUCK.
